UNITED STATES PATENT OFFICE.

SOLOMON WILE, OF ROCHESTER, NEW YORK.

SLICING MACHINE.

Application filed January 12, 1922. Serial No. 528,803.

To all whom it may concern:

Be it known that I, SOLOMON WILE, a citizen of the United States, and resident of Rochester, in the county of Monroe and State of New York, have invented certain new and useful Improvements in Slicing Machines, of which the following is a specification.

The present invention relates to slicing machines and an object thereof is to provide an improved means for feeding toward the cutter a table or carriage on which the material to be sliced is held. Another object of the invention is to provide means for preventing any back lash in the carriage which supports the material to be sliced so that the pressure of the cutter upon the material on the carriage will not shift the carriage and produce uneven slices. A further object of the invention is to provide in connection with a mechanism for feeding the carriage toward the cutter step by step, a friction clutch which will hold the carriage in its shifted position so that it will not be moved backwardly by pressure on the material during the cutting action. Still another object of the invention is to provide a means by which the carriage on which the material to be sliced is arranged may be freed from the feeding or shifting mechanism and also from a back lash clutch to permit such carriage to be shifted away from the cutter. A still further object of the invention is to provide an improved mechanism for feeding the carriage in the direction of the plane of operation of the rotary cutter and driven with said mechanism. Another and still further object of the invention is to provide an improved means for securing the guard 40 for the rotary cutter in operative position.

To these and other ends, the invention consists of certain parts and combinations of parts, all of which will be hereinafter described, the novel features being pointed out 45 in the appended claims.

In the drawings:

Fig. 1 is a plan view of a machine constructed in accordance with this invention showing the carriage in one position;

Fig. 2 is a plan view showing the carriage in still another position;

Fig. 3 is a plan view showing one of the carriages removed;

Fig. 4 is an enlarged detail plan view

showing the manner in which one of the carriages is shifted toward the cutter;

Fig. 5 is an enlarged section on the line 5—5, Fig. 4;

Fig. 6 is a detail view showing the feed adjusting device;

Fig. 7 is an end view of the machine in elevation;

Fig. 8 is a section on the line 8—8, Fig. 1;

Fig. 9 is a detail sectional view showing the manner in which one of the carriages is guided;

Fig. 10 is a view in elevation of the machine from the cutter side; and

Figs. 11 and 12 are detail views showing the guard in two positions.

In the illustrated embodiment of the invention, there has been provided a base 1 from which rise two uprights 2 and 3 connected by an intermediate cross member 4. 75 Connecting the uprights 2 and 3 above the cross piece 4 is a shaft 5 on which a disk or circular cutter 6 is secured as by a nut 7. This shaft is provided with a bevelled pinion 8 which meshes with a crown gear 9, the latter being secured to a shaft 10 journaled in the cross piece 4, said shaft 10 also having a crown gear 11 secured thereto and meshing with a bevelled gear 12 on an operating shaft 13 journaled on the cross piece 4 and in the upright piece 2 and having a crank handle 14 thereon through which movement of the rotary cutter 6 is effected. Operable on the frame and particularly, in this instance, on the side frames 2 and 3 in 90 a direction substantially parallel with the plane of operation of the disk or rotary cutter 6 is a carriage 15. In order to guide this carriage, the guiding surfaces 16 and 17 are provided, respectively, on the side frame pieces 2 and 3. The guide surface 16 is overhung by a projection 18 which cooperates with the upper surface of the carriage, while the guiding surface 17 is overhung by a projecting rib 19 which extends 100 into a groove or recess 20 formed in the side of a depending projection 21 on the side of the carriage 15. The opposite side of this depending projection 21 is engaged by a removable retaining strip 22 secured to the side piece 3 by screws 23.

Movement of the carriage 15 may be effected in any suitable manner but it is pre-

ferred to operate the same so that each rotation of the crank shaft 13 will effect a complete back and forth movement of the carriage 15. This result, in this instance, is obtained by providing a lever 24 pivoted at 25 to the upright 2 and at 26 to one end of a link 27 which in turn is pivoted at 28 to the under side of the carriage 15. The link 24 has pivoted thereto at 29 a link or pitman 30 which in turn is pivoted at 31 at an eccentric point on the crown gear 9, so that motion is transmitted from said crown gear, in the rotation of the latter, to the lever 24 and from the latter by way of link 27 to 15 the carriage 15.

The carriage 15 also acts as a support for a carriage 32, in this instance, in the form of a plate or table guided by guide strips 33 and 34 on the carriage 15 at a right angle 20 to the line of movement of said carriage 15, so that the carriage 32 moves on the carriage 15 on a line substantially at a right angle to the plane of operation of the rotary cutter 6.

25 The movement of the carriage 32 may be effected in any suitable manner. In this instance, the carriage 32 has on its under side a tooth or rack bar 35 with which a pawl 36 is adapted to engage through a tooth 37, this pawl 36 being pivoted at 38 to one arm of a swinging or bell crank member 39 which in turn is pivoted at 40 to the carriage 15. A spring 41 acts between the swinging member 39 and the 35 pawl 36 to maintain the tooth 37 toward the tooth bar 35. To the swinging member or bell crank lever 39, a link 42 is pivoted at 43, this link also being pivoted at 44 to an adjustable lever 45 which is pivoted 40 at 46 to the carriage 15. A spring 47 connects the link 42 with the swinging member 39 and tends to hold the adjustable lever 45, link 42 and swinging member 39 so that the pawl 36 will lie in cooperation with the 45 tooth bar 35. The lever 45 has an extension or arm 48 at one side of the carriage 15 to cooperate with a side face 2^a of the frame piece 2 just prior to the carriage 15 reaching one end of its movement. When this 50 projecting arm 48 cooperates with the frame piece 2, which forms a stop or abutment, the adjustable lever 45 is shifted on its pivot 46 and the link 42 pulls the swinging member 39 against the action of the 55 spring 47 to shift the pivot 38 of the pawl 36 so that the tooth 37 of said pawl will, by engagement with the tooth bar 35, feed the carriage 32 a predetermined distance. When the carriage 15 begins its return 60 movement, the spring 47, in returning the arm 48 to its normal position, will act on the swinging member 39 in the direction to shift the resiliently held pawl 36 so that the tooth 37 will ride over the tooth bar 35.

65 The amount of the feeding of the carriage

32 may be determined by any suitable means. In this instance, there is provided an adjusting screw 49 which is mounted on the adjustable lever 45 and is adapted to cooperate with a fixed stop or abutment 50 on the under side of the table or carriage 15. By adjusting this screw the movement of the adjustable lever 45 after engagement with the face 2^a of the frame piece 2 may be varied, as the position of the arm 48 with reference to the carriage 15 is changed. There may also be employed, in connection with the feeding mechanism for the carriage 32, an indicating means, which, in this instance, is in the form of a pointer 51 80 on the lever 45 operating in a slot 52 in the carriage 15 to cooperate with the scale or indications 53 on the top surface of the carriage 15 adjacent the slot 52.

It is also preferred to employ in connection with the carriage 32 a clutch or other back lash device which will prevent even the smallest amount of movement of the carriage 32 away from the cutter after each feeding action. In this instance, this clutch 85 is in the form of a cam surface 54 on a member pivoted at 55 on the carriage 15, the cam surface 54 being adapted to cooperate with the carriage 32 to prevent the return of the latter while, at the same time, permitting the feeding of said carriage 32 toward the cutter. A spring 56 acts on this cam member 54 to maintain it in cooperation with the carriage 32 while, at the same time, permitting the yielding of said cam 95 member when the carriage 32 is fed toward the cutter.

With the end in view of permitting the carriage 32 to be moved away from the cutter, a controlling rod 57 is employed, this rod having a finger piece 58 through which it may be pulled and having also a pivotal connection at 59 with the pawl 36 so that the latter may be disengaged from the rack bar 35 to permit the carriage being shifted by hand toward its starting position. In order to control also the clutch or cam member 54, the rod 57 has connection through an arm 60 on said clutch member and a shoulder 61 on the rod through which the clutch member 54 is shifted out of engagement with the carriage 32 when the rod 57 is pulled to release the carriage from the pawl 36.

With the end in view of protecting the 120 user of the machine against the rotary cutter 6, the latter may be provided with a guard 62 in the form of a segment of a ring which provides a space between its ends through which the knife may be engaged by the material on the carriage 32. This ring segment is L shaped in a cross section so that it will cover the edge of the knife as well as the front face of said knife adjacent the edge. In this instance, this guard is pivoted on a 130

shaft 63 so that it may be swung away from the knife to permit the cleaning of the latter. There may also be provided a combination stripper and guard for the portion of the 5 knife exposed between the ends of the ring segment. This combination element is indicated at 64 and is pivoted at 65 to one end of the ring segment 62. The other end of this stripper and guard is adapted to be received 10 in a slot 66 in the opposite end of the guard 62, a projection 67 on the element 64 limiting the movement of the element 64 in said opening or recess 66. When the stripper 64 is in its uppermost position, as indicated 15 in dotted lines, in Fig. 10, it protects the user against the knife edge between the ends of the segment 62. When in its lowermost position this stripper lies in engagement with a grooved collar 68 which is on the 20 shaft 5 of the cutter 6, its upper edge at 69 acting to strip from the knife 6 any material which may be cut by the knife. The guard 62 and the stripper 64 are held in operative position by a latch or detent 70 which is 25 pivoted at 71 to the frame piece 3 and has a portion engaging the guard 62 and the stripper 64 at the pivot 65. This detent also has an operating portion 72 which cooperates with the under side of the upper portion of 30 the frame 3 to define the detaining position of the detent 70. Depression of the portion 72 shifts the detent out of engagement with the pivot 65 and permits the guard 62 with the stripper 64 to be swung away from the 35 knife on the shaft 63.

For catching and holding the material which is cut by the cutter 6, there may be provided a shelf 73 which has a ledge 74 at its rear edge provided with a projection 75 40 adapted to engage in a notch 76 in the guard 62 adjacent the pivot 65, so as to support the shelf 73 in a position where the material cut by the knife 6 will be caught by said shelf. It is apparent that this shelf is 45 detachable from the guard 62 by elevating the latter so as to bring the projection 75 out of interlocking relation with the guard.

With the end in view of holding the material on the carriage or table 32, there may be 50 provided a clamping means which, in this instance, comprises a post 32^a rising from the carriage 32 at one side thereof and having a clamping arm 77 adjustable thereon. This clamping arm has its under side curved 55 and provided with a plurality of knife edges 78 separated by pins or projections 79. These knife edges and pins or projections lie substantially over the edge of the table 32 so that the edge of the table with this 60 clamp serve for effectively holding the material to be sliced. The curved construction of the clamping member is particularly adapted for holding meat as it tends to force the meat toward the center of the clamping 65 member and prevent the slipping of the

meat under such clamping member. This clamping member may be adjustable on the upright 32^a through a collar 80 guided on such upright, this collar carrying a set screw 81 which locks the collar on the upright. 70 At the free end of the clamp the table or carriage 15 is provided with a flange 82 which, in this instance, is formed in one piece with the guide 84. This flange cooperates with the clamp to confine the material to be cut 75 to the table or carriage 32.

The operation of the invention will be understood from the foregoing but it may be summarized as follows: The material to be sliced is placed on the carriage 32 and is 80 held there by the clamping arm 77, the knife edges 78 of which are disposed vertically over the carriage 32 so that such edge cooperates with the knife edges to hold the material. The carriage is then adjusted so that the material lies slightly to one side of the plane of operation of the cutter 6. Upon the turning of the shaft 13, the cutter is rotated and the carriage 15 is reciprocated. After the carriage 15 reaches its position just prior 90 to its advance toward the cutter, the arm 48 of the bell crank lever 45 cooperates with the overhanging projection 18, thus effecting the shifting of the pawl 36 to shift the carriage 32 on the carriage 15. The amount of 95 this shifting is determined by adjusting the set screw 49 so that the pointer 51 points to the desired division of the scale 53. As the carriage 32 is advanced, it is held in this advanced position by the clutch 54. After the 100 carriage 32 has reached the limit of its movement toward the rotary knife or cutter 6, the carriage with the material is shifted away from the cutter, this being effected by pulling on the controller 58 to disengage 105 the pawl 36 from the ratchet bar 35 and, at the same time, to throw the clutch 54 out of cooperation with the carriage 52. The material is then adjusted on the carriage 32 so as to cause the desired amount to project beyond the edge of said carriage and the operation is continued as before. The guard for 110 the cutter is mounted to swing downwardly on the shaft 63 in order to permit the knife to be cleaned. This guard has a combined stripper and guard which may lie in a position where it acts to strip the meat from the cutter blade and also in a position where it acts to cover the exposed portion of the blade. The detent 70 is employed to cooperate with 115 the guard adjacent the pivotal connection between the latter and the combined stripper and guard. This detent places the guard 62 under such tension as to throw the latter 120 away from the plane of the cutter 6, as shown in Fig. 12 in order that there will be no interference between the cutter and the guard during the cutting action. The combined stripper and guard interlocks with 125 the guard 62, in such a manner as to cause 130

the guard 62 to move into guarding relation with the cutter, as shown in Fig. 11.

What I claim as my invention and desire to secure by Letters Patent is:—

- 5 1. A slicing machine comprising a frame, a cutter movable on the frame, a carriage movable on the frame parallel with the plane of operation of the cutter, a carriage movable transversely of the plane of operation of the cutter, mechanism for shifting the first mentioned carriage on the second mentioned carriage comprising a lever pivotally mounted in the first mentioned carriage, a second lever cooperating with 10 15 with the first mentioned carriage to shift the latter step by step, a third lever pivotally mounted on the first mentioned carriage and adapted to cooperate with the frame when the first mentioned carriage reaches the first position to shift said lever in one direction, and a link connection between the third mentioned lever and the first mentioned lever.
2. A slicing machine comprising a frame, 25 a cutter movable on the frame, a carriage movable on the frame parallel with the plane of operation of the cutter, a carriage movable transversely of the plane of operation of the cutter, mechanism for shifting the first mentioned carriage on the second mentioned carriage comprising a lever pivotally mounted in the first mentioned carriage, a second lever cooperating with 30 the first mentioned carriage to shift the latter step by step, a third lever pivotally mounted on the first mentioned carriage and adapted to cooperate with the frame when the first mentioned carriage reaches the first position to shift said lever in one direction, a 35 link connection between the third mentioned lever and the first mentioned lever, and an adjusting means cooperating with said first mentioned lever to vary the movement of the third mentioned lever.
- 45 3. A slicing machine comprising a frame, a cutter movable on the frame, a carriage supporting the material to be sliced movable transversely of the plane of operation of the cutter, mechanism for shifting the 50 carriage toward the cutter, and a friction clutch arranged to cooperate with said carriage to prevent the return thereof after the feeding movement.
4. A slicing machine comprising a frame, 55 a cutter movable on the frame, a carriage supporting the material to be sliced movable transversely of the plane of operation of the cutter, mechanism for shifting the carriage toward the cutter, a friction clutch

arranged to cooperate with said carriage to prevent the return thereof after the feeding movement, and a common means for rendering the shifting means and the clutch inoperative to permit the carriage to be shifted away from the cutter.

5. A slicing machine comprising a frame, a cutter movable on said frame, a carriage for supporting the material to be sliced, movable transversely of the plane of operation of the cutter, mechanism for shifting the carriage toward the cutter comprising a pawl and ratchet, a friction clutch for holding the carriage in the position to which it is adjusted by the pawl and ratchet, and a common controlling member for rendering the pawl and ratchet and the clutch inoperative to permit the movement of the carriage away from the cutter.

6. A slicing machine comprising a frame, a cutter movable on the frame, a carriage 80 movable on the frame parallel with the plane of operation of the cutter, a carriage for supporting the material to be sliced, movable on the first mentioned carriage transversely of the plane of operation of the 85 cutter, a lever pivotally mounted on the first mentioned carriage, a second lever pivotally mounted on the first mentioned lever, said levers being movable together to shift the second mentioned carriage step by step, a pivoted friction clutch mounted on the first 90 mentioned carriage and cooperating with the second mentioned carriage to hold the latter in its adjusted position on the first mentioned carriage, and a common controlling member for shifting the second lever and the pivoted clutch to permit the second mentioned carriage to be moved away from the cutter on the first mentioned carriage.

7. A slicing machine comprising a frame, a cutter movable on the frame, a carriage movable on the frame parallel with the plane of operation of the cutter, a carriage for supporting the material to be sliced, 105 movable on the first mentioned carriage transversely of the plane of operation of the latter, a shaft journalled on the frame and supporting said cutter, a gear on said shaft, a crown gear mounted to turn on the frame 110 and meshing with said gear on the cutter shaft, a lever pivoted to the frame and having a link connection with the first mentioned carriage, a link connecting said lever with the crown gear at a point eccentric 115 to the axis of turning of the latter, and means for turning said crown gear.

SOLOMON WILE.
